UNITED STATES PATENT OFFICE

EDWARD W. N. BOOSEY, OF DETROIT, MICHIGAN.

FLOOR-PLATE FOR CLOSET-BOWLS AND THE LIKE.

1,112,760.

Specification of Letters Patent.

Patented Oct. 6, 1914.

Application filed July 17, 1913. Serial No. 779,429.

To all whom it may concern:

Be it known that I, EDWARD W. N. BOOSEY, a citizen of the United States, residing at Detroit, county of Wayne, State of Michigan, have invented a certain new and useful Improvement in Floor-Plates for Closet-Bowls and the like, and declare the following to be a full, clear, and exact description of the same, such as will enable others skilled 10 in the art to which it pertains to make and use the same, reference being had to the accompanying drawings, which form a part of this specification.

This invention relates to floor plates utilized in securing closet bowls to the waste pipe, and the object of the invention is a plate or coupling for the purpose stated by means of which the usual lead pipe connection between the bowl and the closet bend 20 may be dispensed with and the bend made entirely of cast iron.

A further object is a floor plate of such construction as to enable it to be readily calked to the closet bend as hereinafter 25 shown and to provide a space into which excess packing material, such as putty or the like, usually used as a gasket between the plate and flange of the closet bowl, may be forced in securing the parts together.

30 The structure by which these and other objects of the invention may be accomplished is hereinafter more fully described and claimed and shown in the accompanying drawings in which—

35 Figure 1 is an elevation, partly in section, showing the lower part of a closet bowl secured to a bend by means of my improved floor plate. Fig. 2 is a sectional view in perspective of the floor-plate. Fig. 3 is a vertical section taken on the line $x-x$ of Fig. 2. Fig. 4 is a vertical section taken on the line $y-y$ of Fig. 2.

Similar characters refer to similar parts throughout the drawings and specification.

45 The plate is substantially circular in form having a central aperture 1, a frusto-conical portion 2, and a laterally extending circumferential flange 3. The bottom of the bowl 5 rests upon the floor plate and is secured thereto by means of bolts passing through 50 the slots 4 into openings provided in the flange 6 of the bowl.

As may be seen more clearly in Fig. 3, the laterally extending flange 3 of the floor plate is recessed at 7 to form a gasket receiving space and midway of the length of

the cone-shaped portion 2 of the plate is a vertically extending circumferential rib 8 and the space between the rib 8 and the recess 7 is so positioned that the packing material placed in the gasket recess will be forced out into the channel 9 when compressed between the plate and bowl instead of outwardly toward the edge of the flange on the bowl where it would be exposed to view between the flanges 3 and 6.

The upper vertical portion 10 of a bend or other fitting to which the floor plate is secured, is preferably circumferentially grooved, the object of which is not only to provide means whereby said vertical portion may be easily cut to the desired height, but also to provide means to be utilized in calking the plate to the bend. As may be seen in Fig. 3, the circumferential rib 8 is spaced 70 a slight distance from the wall of the bend 10 which provides a channel 11 into which lead may be placed and the wall 8 being vertically positioned, the lead may be rammed into place against the bend and into the 75 grooves therein, and the rib 8 prevents it from creeping upward on the cone surface and provides a solid wall for holding the lead in place.

The base of the bowl 5 is provided with a 80 depending circular flange 12 adapted to enter in the open end of the bend 10 when the parts are assembled and the bowl secured to the plate by means of bolts heretofore mentioned. By this arrangement a tight joint 85 is secured and the calking of the joint is done substantially on a level with the floor, as may be seen in Fig. 1, whereas with bends provided with a hub and using short length of lead pipe the calking is necessarily performed at a considerable distance below the floor level and in an inconvenient position. With the device herein disclosed the opening in the floor through which the upper 90 end of the bend projects need be but slightly greater in diameter than the bend and the calking may be performed much more readily and cheaply.

The flange 3 of the plate is provided with a short depending circumferential flange 13 100 which is adapted to rest directly upon the floor whereby a space is provided for the head of the bolts which secure the bowl to the plate, and, as may be seen more clearly in Fig. 4, the plate is provided with two oppositely positioned flat portions 20 in which the slots 4 are placed at which points the

2

plate is not truly conical in shape as the flange 3 extends laterally at such points level with the bottom of the recess 7 to and terminates at the vertical wall 8, which with the upper end of the bend or fitting forms a circular space about the bend to receive the calking material as above stated.

It is to be noted that the conical portion of the plate is comparatively short vertically and does not extend but slightly, if at all, below the floor boards and consequently the opening in the floor may be less in diameter than is usual with other types of plates. With cement floors the cementitious material may be brought into contact with the bend and a shallow cone shaped depression formed in the upper surface of the floor to receive the floor plate in which construction the floor plate does not extend below the floor. The plate may be secured to the floor, if desired, by means of screws 21 passing through apertures provided in the flange 3 as shown in Figs. 2 and 3.

25 Having thus briefly described my invention and its utility, what I claim and desire to secure by Letters Patent of the United States is—

1. A floor plate comprising an apertured depending cone-shaped portion provided with a flange extending laterally from the base of the cone, a vertically extending circular rib upon the inner surface of the cone substantially midway of its length, said flange having portions upon opposite sides of the plate extending to said circular rib providing bolt receiving pockets substantially as described.

2. A floor-plate comprising a centrally apertured cone shaped portion provided with a flange extending laterally from the base of the cone, and a rib upon the inner surface of the cone-shaped portion positioned substantially midway of its length whereby a channel for calking material is formed between the rib and a fitting positioned within the aperture, and a channel

between the rib and the base line of the cone for excess packing material, said flange having portions upon opposite sides of the plate 50 extending horizontally to said rib providing pockets on the under side of the plate to receive bolt heads.

3. A floor plate comprising a centrally apertured cone shaped portion provided 55 with a flange extending laterally from the base of the cone, and a rib upon the inner surface of the cone shaped portion extending at right angles to the flange and terminating below the upper surface thereof, said rib 60 being so positioned on the cone that a channel for calking material is formed between the rib and a fitting positioned within the aperture in the cone, and a channel between the rib and the base line of the cone for excess packing material, said last named channel being bridged upon opposite sides of the plate, said bridges being coextensive with the flange and providing pockets upon the under side thereof. 70

4. A floor plate comprising a centrally apertured shallow cone-shaped portion provided with a circumferential flange extending laterally from the base of the cone, and a vertically extending circular rib upon the 75 inner surface of the cone-shaped portion substantially midway of its length whereby a channel for calking material is provided between the rib and a fitting positioned within the aperture, and also a channel between the rib and the base line of the cone, said flange having portions upon opposite sides of the plate extending horizontally to said rib, said extending portions being slotted for the reception of fastening bolts, 80 said rib, flange, and cone-shaped portion, being formed integrally. 85

In testimony whereof, I sign this specification in the presence of two witnesses.

EDWARD W. N. BOOSEY.
